C. A. Snow & Co.

UNITED STATES PATENT OFFICE.

HENRY ECKLER AND JOHN WOESNER, OF SEYMOUR, INDIANA.

ROAD-WAGON.

SPECIFICATION forming part of Letters Patent No. 461,073, dated October 13, 1891.

Application filed May 28, 1891. Serial No. 394,335. (No model.)

To all whom it may concern:

Be it known that we, HENRY ECKLER and JOHN WOESNER, citizens of the United States, residing at Seymour, in the county of Jackson and State of Indiana, have invented a new and useful Buckboard and Road-Wagon, of which the following is a specification.

The invention relates to improvements in vehicles.

10 The object of the present invention is to simplify and improve the construction of that class of vehicles known as "buckboards" and "road-wagons" and to enable the same to have a free and easy motion.

15 The invention consists of the construction and novel combination and arrangement of parts, hereinafter fully described, illustrated in the accompanying drawings, and pointed out in the claim hereto appended.

20 In the drawings, Figure 1 is a rear elevation of a buckboard and road-wagon constructed in accordance with this invention. Fig. 2 is a reverse plan view. Fig. 3 is a detail perspective view of one of the springs.

25 Referring to the accompanying drawings, 1 designates a body having secured to its bottom spring-bars 2, which are arranged transversely of the bottom near the ends thereof, and secured to the lower faces of the spring-bars are

30 U-shaped springs. The U-shaped springs 3 have their sides provided with coils 4 and receive between their sides front and rear axles 5 and 6, which are secured to the body by means of said spring. The axles are provided

35 near their ends with bearings 7, arranged on the upper faces of the axles and adapted for the reception of U-shaped clips 8, which are

provided at their ends with eyes which are connected by a bolt or tie 9. The bolt or tie 9 is arranged below the axle and is engaged 40 by a hook 10, formed at the outer end of the U-shaped spring 3. The depending U-shaped clip is adapted to swing, thereby permitting free and independent action of the springs.

The axles are connected by a reach 11, 45 which has its rear end rigidly secured to the rear axle, and is pivotally connected to the front axle and is braced by rods 12, extending from about midway its length to the rear axle.

50 It will be seen that the buckboard is simple and inexpensive in construction and has a free and easy motion, and that the various springs have free and independent action.

55 What we claim is—

The combination of the body, the axles provided with bearings, the depending U-shaped clips arranged in the bearings, the ties connecting the ends of the clips, and the U-shaped springs receiving within their sides 60 the axles and having their upper ends secured to the bottom of the body and provided at their lower ends with hooks to engage the said ties and having coils intermediate their ends, substantially as described.

65 In testimony that we claim the foregoing as our own we have hereto affixed our signatures in presence of two witnesses.

HENRY ECKLER.
JOHN WOESNER.
